UNITED STATES PATENT OFFICE.

THADDEUS C. JOY, OF TITUSVILLE, PENNSYLVANIA.

STEAM-GENERATOR.

SPECIFICATION forming part of Letters Patent No. 292,822, dated February 5, 1884.

Application filed January 26, 1883. (No model.)

To all whom it may concern:

Be it known that I, THADDEUS C. JOY, a citizen of the United States, and a resident of Titusville, in the county of Crawford and State of Pennsylvania, have invented a new and useful Improvement in Steam - Generators, of which the following is a specification.

My invention is more particularly applied to and is an improvement in form of construction of the steam-generators for which I have previously obtained Letters Patent as follows, viz : No. 209,895, November 12, 1878 ; No. 233,624, October 26, 1880; No. 258,075, May 16, 1882, and No. 269,582, December 26, 1882, all of which are for sectional steam-generators of various forms, my present invention being a change in form of the segments, whereby I simplify the construction, lessen the cost, and increase the area of the heating-surface.

My improvement is better illustrated and understood by reference to the accompanying drawings, in which Figure 1 represents a horizontal section of my generator on line XX, Fig. 2; Fig. 2, a vertical section on line YY, Fig. 1; and Fig. 3, an isometric view of one section; Fig. 4, a similar view of one section as the segments are extended downward, inclosing the fire-box; and Fig. 5, a view and cross-section of narrow plates which may be inserted between the projections, completing the inclosure of the fuel-reservoir.

Similar letters refer to similar parts in the several figures.

A is the generator, composed of the segments B, shown in the drawings as eight in number, but may be more or less, as desired. These segments are constructed hollow, as shown, and with the adjoining edges guttered or grooved, the upper part of each segment having an inward radial projection, E. When the segments are placed in position, as shown in Figs. 1 and 2, they form the outside or shell of the generator, inclosing the fire-chamber, and with the segmental annular water-chamber D, the radial projections E forming the segmental steam-dome, the guttered sides forming the direct flues M. Water and steam connections are made between the adjoining sections at top and bottom, and with the external water and

steam pipes in the usual manner. These are 50 not shown in the drawings, as they form no part of my improvement.

G is the casing or jacket inclosing the generator and forming the smoke-chamber H, between the return-flues F and the smoke-pipe I, leading to the chimney.

So far as described the generator is of the form covered in the previous patents to me, above referred to. I now construct the segments B with the thin, flat, and hollow projection K, extending into the fire-chamber, the hollow space forming a part of the segmental water-chamber D, and also having free opening into the segmental steam-dome E. These projections may extend inward until the ends 60 of the different sections meet, or nearly so, forming and inclosing the central opening, L, which may be used as a fuel-reservoir, if desired. The spaces between the different sections form the direct flues M, which bring the 65 products of combustion in close contact with the inner sides of the segments B and the sides of the projections K. The guttered sides of the segments B form the return-flues F, which connect with the direct flues M at the top by 70 reason of the inner wall of the gutters being shorter than the outer wall thereof. The sides of the steam-drums E are inclined or beveled from their upper edge and inner vertical edge toward the lower outer corner, f, thereby forming 75 a passage, m, over the end of the inner wall of the guttered side, as indicated by the arrow. The upper portions of the sides of these drums are also provided with depressions or semicircular recesses b, which segments, 80 when placed together, form circular openings for the insertion of a suitable device into the return and direct flues, for the purpose of 85 cleaning them. The sides of the projection K are shown in the drawings as corrugated, which 90 is the manner in which I prefer to make them, as it materially increases the heating-surface. They may, however, be made flat, if desired. These projections may extend inward until 95 the ends of the two adjoining sections meet, completely inclosing the fuel-reservoir L; or they may stop short of that point, leaving spaces between, which may be filled, if desired,

by narrow strips inserted between the ends of the projections, in that manner completing the inclosure of the fuel-reservoir. The view and cross-section of the narrow strips are shown in Fig. 5. In the drawing Fig. 2 the segments B are shown as standing on and connected to an annular water-ring around the fire-box C. If desired, the segments B may be extended below the projections K, in themselves forming the walls of the fire-box, as shown in Fig. 4.

I claim as my invention—

1. In a circular segmental steam-generator, the inward projections K from the segments B, constructed as described, and with free water communication with the water-chamber D, and the steam-drum E, the inner ends of said projections forming the walls of the central fuel-reservoir, L, substantially as described, and for the purposes herein set forth.
2. In a segmental steam-generator, the hol-

low segment having guttered sides and provided with a radial steam-drum at its top, and hollow projections forming a part of the wall of the fuel-reservoir, having corrugated sides, 25 substantially as shown and described.

3. In a circular steam-generator, the combination, with the outer casing, having a smoke-pipe leading therefrom, and an annular water-chamber located above the grate-bars, 30 of a series of hollow segments having guttered sides which form return-flues, radial steam-drums at the upper ends, and the corrugated projections which rest upon said annular chamber, forming the wall of the fuel-reservoir and direct flues between their opposite sides, substantially as described.

THADDEUS C. JOY.
